(57) **CLAIM**

The ornamental design for a video doorbell mount, as shown and described.

DESCRIPTION

FIG. 1 is a top, front side perspective view of a mount for a video doorbell mount showing our new design;

FIG. 2 is a top elevation view thereof;

FIG. 3 is a bottom elevation view thereof;

FIG. 4 is a front plan view thereof;

FIG. 5 is a rear plan view thereof;

FIG. 6 is a left side elevation view thereof; and,

FIG. 7 is a right side elevation view thereof.

The broken line showing is included for the purpose of illustrating portions of the video doorbell mount and forms no part of the claimed design.
